PAINT CAN ATTACHMENT FOR DRAINING A PAINT BRUSH

Ward W. Bainbridge, 493 Ramapo Valley Road,
Oakland, N.J. 07436

Filed Nov. 1, 1965, Ser. No. 87,965

Term of patent 14 years

(Cl. D9—2)

FIGURE 1 is a perspective view of a paint can attachment for draining a paint brush showing my new design;
FIGURE 2 is a plan view;
FIGURE 3 is a side elevational view; and
FIGURE 4 is a sectional view in elevation taken along the line 4—4 of FIG. 2 looking in the direction of the arrows.

The partial broken line showing of the paint can in FIGURE 1 is for illustrative purposes only.

I claim:

The ornamental design for a paint can attachment for draining a paint brush, as shown and described.
